Frank Kelly *Attestor*

UNITED STATES PATENT OFFICE.

SAMUEL D. ROBERSON, OF MOUNDS, ILLINOIS.

SWITCH-LIST HOLDER.

Application filed October 26, 1923. Serial No. 670,944.

To all whom it may concern:

Be it known that I, SAMUEL D. ROBERSON, a citizen of the United States, residing at Mounds, in the county of Pulaski and State of Illinois, have invented certain new and useful Improvements in Switch-List Holders, of which the following is a specification.

This invention has reference to a switch list holder for switchmen's use at night and provides means whereby the list may be suitably supported from a lantern so as to be visible and distinct at all times.

A further object of the invention is to provide a switch list holder which may be stamped from a single blank and readily attached to a lantern so as to properly support the list.

Various other objects and advantages of the invention will become apparent from the following disclosure.

In the drawing:

Figure 1 is a view showing the manner of applying the invention to a lantern, and Figure 2 is a plan view of the holder before being bent into shape.

In carrying out the invention, the holder is stamped from a sheet of metal or other suitable material and comprises an arcuate body portion 10 having a plurality of attaching tongues 11 projecting outwardly from the inner longitudinal edge thereof and attaching strap 12 extending outwardly from the opposite longitudinal edge. At relatively spaced points the body portion 10 is slotted to provide spring clips 13 for holding a switch list as indicated at 14, the list being inserted between the spring clips and the body portion.

In attaching the holder to a lantern 15, the attaching tongues 11 are bent downwardly from the body portion and soldered or otherwise secured to the body of the lan-

tern as illustrated in Figure 1. The straps 12 are likewise bent downwardly from the body portion and have their lower ends soldered to the base 16 of the lantern, the straps being of greater length than the tongue 11 so as to support the body portion in a substantially horizontal plane.

It may thus be seen that the switch list 14 will be supported in such a position as to be distinctly illuminated by the lantern and, hence, easily read by the switchman at night. The spring clips 13 enable the switch list to be readily changed whenever desired and prevents loss or detachment of the list from the holder when in use.

Although the holder has been described above in connection with switch lists for switchmen, it is to be understood that the invention is adapted for general use and is, moreover, susceptible of various changes in construction, design, and arrangement of parts without departing from the spirit of the invention.

From the foregoing it is thought that the object and advantages of the invention can be readily understood and that further detailed description thereof is unnecessary.

What is claimed is:

An article holding attachment for lanterns comprising a member stamped from a single blank of material and presenting a body portion having outstanding elements adjacent the opposite longitudinal edges thereof, said elements being bendable angularly from the body portion to provide attaching elements therefor and said body portions having elements cut out therefrom to define spring clips for holding a list or other article to the said body portion.

In testimony whereof I affix my signature.

SAMUEL D. ROBERSON.
